UNITED STATES PATENT OFFICE.

ANDREW HUNTER, OF SAN FRANCISCO, CALIFORNIA.

DESIGN FOR A HOSE-SUPPORTER.

SPECIFICATION forming part of Design No. 35,549, dated January 7, 1902.

Application filed December 2, 1901. Serial No. 84,481. Term of patent 14 years.

To all whom it may concern:

Be it known that I, ANDREW HUNTER, a citizen of the United States of America, and a resident of the city and county of San Francisco and State of California, have invented and produced a new and useful Design for Hose-Supporters, of which the following is a full, clear, and exact description, reference being had to the accompanying drawing, forming part of this specification, in which the figure is a front view of a hose-supporter, showing my new design.

As shown in the drawing, the leading or material feature of my design consists in a waist strap or belt A, having the two end portions *a a* brought together at the front and crossed at an angle resembling somewhat a St. Andrew's cross, with the top limbs or members prolonged and united and the lower limbs or members also prolonged, but left free to hang loosely below the crossing-point B. On opposite sides of the point of intersection B two shorter straps C C, depending perpendicularly, or nearly so, downward, spring or 25 diverge from the waist-strap at points *d d*

above the central cross B and also extend across the lower members *a* of the waist-strap below the cross, from which point of intersection with the lower members of the waist-strap these two shorter straps extend for a distance about equal to the length of such waist-strap members. From the points *d*, where the set of shorter straps C unite with or spring from the waist-strap, a bar E extends horizontally, or nearly so, from one side to the other, 30 and below the crossing-point a second cross-bar F unites the depending members at a point below the cross.

Having thus described my invention, what I claim as new, and desire to secure by Letters 40 Patent, is—

The design for a hose-supporter, as herein shown and described.

In testimony whereof I have signed my name to this specification in the presence of 45 two subscribing witnesses.

ANDREW HUNTER.
